[57] CLAIM

The ornamental design for a gear housing, as shown and described.

DESCRIPTION

FIG. 1 is a perspective view of a gear housing showing my new design;

FIG. 2 is a reduced side elevational view thereof;

FIG. 3 is an enlarged side elevational view of the side opposite that shown in FIG. 2;

FIG. 4 is a reduced top plan view thereof;

FIG. 5 is a reduced bottom plan view thereof;

FIG. 6 is a reduced end elevational view taken from the bottom of FIG. 2;

FIG. 7 is a reduced end elevational view taken from the top of FIG. 2.

The cross line shading which is partially shown on the body of the gear housing is understood to repeat uniformly across that surface.
